(57) **CLAIM**

The ornamental design for a display screen portion with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 depicts a first embodiment of a display screen portion with icon, showing our new design;

FIG. 2 depicts a second embodiment thereof;

FIG. 3 depicts a third embodiment thereof; and,

FIG. 4 depicts a fourth embodiment thereof.

The dash-dot broken line in each figure illustrates a display screen portion that forms no part of the claimed design. The remaining broken lines, including all text and numerals shown, illustrate portions of the icon design that form no part of the claimed design.
